UNITED STATES PATENT OFFICE

115,207

DESIGN FOR A COMBINED SALT AND PEPPER HOLDER

Ansgarius H. Johnson, Chicago, Ill.

Application February 27, 1939, Serial No. 83,222

Term of patent 3½ years

To all whom it may concern:

Be it known that I, Ansgarius H. Johnson, a citizen of the United States and a resident of Chicago, county of Cook and State of Illinois, have invented a new, original and ornamental Design for a Combined Salt and Pepper Holder, of which the following is a specification, reference being had to the accompanying drawing, forming a part thereof, in which Fig. 1 is a view in side elevation of a combined salt and pepper holder showing my new design, Fig. 2 is a top plan view thereof, and Fig. 3 is a view in end elevation of the same.

I claim:

The ornamental design for a combined salt and pepper holder, substantially as shown.

ANSGARIUS H. JOHNSON,
